COMBINED DITCHING TOOTH AND ADAPTER FOR EARTH WORKING MACHINES

Paul H. Nunn, 1111 N. Anita Ave., Oklahoma City, Okla.

Filed Feb. 3, 1964, Ser. No. 78,494

Term of patent 14 years

(Cl. D39—1)

FIG. 1

FIG. 2

FIG. 3

FIG. 4

FIG. 1 is a rear perspective view of a combined ditching tooth and adapter for earth working machines embodying my new design;

FIG. 2 is a front perspective view thereof;

FIG. 3 is a rear elevation view thereof;

FIG. 4 is a left side elevation view of the combined ditching tooth and adapter for earth working machines.

I claim:

The ornamental design for a combined ditching tooth and adapter for earth working machines, as shown.
